UNITED STATES PATENT OFFICE.

JOSEPH H. NORTON, OF MULLINVILLE, KANSAS.

RAILWAY-TIE.

No. 888,729.

Specification of Letters Patent.

Patented May 26, 1908.

Application filed September 3, 1907. Serial No. 391,154.

To all whom it may concern:

Be it known that I, JOSEPH H. NORTON, a citizen of the United States, residing at Mullinville, in the county of Kiowa and State of Kansas, have invented certain new and useful Improvements in Railway-Ties, of which the following is a specification.

This invention relates to railroads and more particularly to ties therefor and has for its object to provide a plastic railroad tie which is simple in structure and arrangement and which is provided with means for attaching rails thereto.

Another object is to provide a tie including strengthening means of a novel arrangement.

Other objects and advantages will be apparent from the following description and it will be understood that changes in the specific structure shown and described may be made within the scope of the claims without departing from the spirit of the invention.

In the drawings forming a portion of this specification, and in which like numerals of reference indicate similar parts in the several views, Figure 1 is a transverse section of a track laid upon the present form of tie; Fig. 2 is a horizontal longitudinal section of the tie; Fig. 3 is a top plan of the tie; Fig. 4 is a transverse section through one of the wear plates on line 4—4 of Fig. 3. Fig. 5 is an elevational view of a modified form of tie.

Referring now to the drawings, the present tie comprises a rectangular plastic body portion 5 having embedded therewith two longitudinally extending parallel strengthening members 6 and 7. Each of these strengthening members comprises a plurality of relatively small metallic rods 8 which are bound together by a continuous wire 9 wrapped therearound and a connecting wire 10 is engaged through the inner portions of the alternate helices of the two wires 9, the wire 10 being engaged through the helices of one wire 9 and then through those of the other so that it traverses the space between the two strengthening members diagonally. A wire 11 is engaged through the remaining helices of the two wires in a similar manner.

There is thus formed a web of interlaced wires between the two strengthening members.

A recess 12 is formed in the upper face of the tie adjacent to each end thereof, and in each of these recesses there is disposed a transversely extending wear plate 13. Openings 14 are formed through the wear plates and register with interiorly threaded pipe nipples 15 embedded vertically in the tie. Longitudinally alining rail-engaging clamp members 16 are disposed upon the wear plates in spaced relation at their inner ends and have openings 17 registering with those of the wear plates for the reception of bolts 18 engaged through the clamps and wear plates and into the nipples.

In use, the rails are disposed upon the wear plates between the clamp members, the latter being positioned to clamp against the base flanges of the rail, and it will be understood that the wear plates protect the tie from the rails. By reason of the character of the strengthening members, they are possessed of some resilience and thus, should the tie become cracked, they will permit the ends thereof to move slightly independently of each other, and thus prevent the appearance of more than one crack. If desired, the tie may be formed with separate plastic end portions, as shown in Fig. 5.

What is claimed is:

In a tie, the combination with a plastic body portion, a spaced rail attaching means carried thereby, a plurality of longitudinally extending strengthening members embedded within the body portion in spaced relation, each of said members including a plurality of rods and a binding wire wrapped around said rods, and a plurality of wires engaged beneath the helices of said binding wires and extending diagonally across the space between the strengthening members.

In testimony whereof I affix my signature, in presence of two witnesses.

JOSEPH H. NORTON.
